United States Patent Office.

HUGH M. PHINNEY, OF CAMBRIDGE, MASSACHUSETTS.

Design No. 3,618, dated August 17, 1869.

DESIGN FOR A HOT-AIR REGISTER.

The Schedule referred to in these Letters Patent and making part of the same.

To all whom it may concern:

Be it known that I, HUGH M. PHINNEY, of Cambridge, in the county of Middlesex, and State of Massachusetts, have invented or produced a new Design for a Hot-Air Register; and I do hereby declare that the following, taken in connection with the drawings, which accompany and form part of this specification, is a description of my invention sufficient to enable those skilled in the art to practise it.

My invention relates to a design in scroll or open fret-work, for registers of hot-air pipes.

This design is shown in the accompanying drawing, which represents a top view of a register-plate, and the essential parts of the design consist in the diagonally-crossing bars *a a*, at the centre of the figure, and the four scroll-pieces *b c d e*, surrounding the same, the width of every bar, or the parts of the casting between every two adjacent openings in the figure, being

about the same throughout the figure, and being as narrow as is consistent with strength, the parts of the figure being so arranged as to leave the plate sufficiently open for free passage through it of the hot air.

The boundary *f* of the register-plate is not unlike that of other registers, and so far as relates to the extreme outer parts of the figure, they are not essential to the design, which is intended for round as well as square registers, the round register-plate taking in the centre-bars *a* and scroll-bars *b c d e*, having the same relative arrangement as seen in the drawing.

I claim the design for a hot-air register, substantially as shown and described.

HUGH M. PHINNEY.
